UNITED STATES PATENT OFFICE

WILLIAM L. SEIBERT, OF FORT MONMOUTH, NEW JERSEY

RADIO SIGNALING SYSTEM

Application filed March 28, 1929. Serial No. 350,749.

(GRANTED UNDER THE ACT OF MARCH 3, 1883, AS AMENDED APRIL 30, 1928; 370 O. G. 757)

The invention described herein may be manufactured and used by or for the Government for governmental purposes without the payment to me of any royalty thereon.

5 This invention relates to radio communication systems, and more particularly to transmitting and receiving circuits using vacuum tubes. The systems used previously have ordinarily included substantially complete 10 separate circuits and tubes for transmitting and receiving.

15 One of the objects of my invention is to utilize a single vacuum tube and associated circuits for both transmitting and receiving, thus effecting a reduction in quantity 20 of apparatus and simplification of circuits required.

A further object is to provide automatic change of plate current as required for the 25 purposes of transmitting and receiving.

A still further object is to utilize a single oscillating tube circuit for both transmission and reception, thus enabling the transmitter and receiver to operate on substantially the 30 same radio frequency.

A clear understanding of the invention may be had by reference to the following description of a complete embodiment which is illustrated in the accompanying drawing.

35 In this drawing there is shown a schematic arrangement of a vacuum tube oscillator connected to a tuned loop antenna circuit. A telegraph sending key, included in the plate circuit, operates to short-circuit the series resistance in the plate circuit so that full 40 plate voltage is impressed on the tube while transmitting and reduced plate voltage is provided while receiving, as is necessary to obtain sensitive reception.

45 Referring now to the drawing, a vacuum tube oscillator of the usual form is represented at 1. This is connected to the tuned circuit consisting of loop antenna 2, fixed ratio condensers 3 and 4, and variable condenser for frequency adjustment 5. Blocking condenser 6 serves to insulate the d. c. plate potential from the tuned circuit. The negative grid bias potential is maintained by 50 potentiometer 7 thru radio frequency choke coil 8. The potentiometer 7 is by-passed for

radio frequencies by condenser 9. The plate current is supplied from the battery shown, the plate circuit including 10, the primary of an audio transformer providing coupling to an audio amplifier. The plate circuit also includes a large resistor 11 and its audio signal by-pass condenser 12. The radio frequency choke coil 13 and condenser 14 serve to prevent short-circuiting the radio frequency potentials present in the loop 55 circuit. A telegraph sending key 15 operates to short-circuit the primary 10 of the audio transformer and the large series resistance 11, so that full plate voltage will be impressed on the tube for transmitting. A 60 large radio frequency current is then set up in the tuned loop circuit. When the telegraph sending key 15 is opened, the plate current is greatly reduced and the circuit oscillates weakly, as is required to obtain 65 sensitivity for heterodyne reception of signals. The adjustment of the oscillation amplitude, as required for most sensitive 70 reception, is precisely controlled by the grid potentiometer 7.

75 The circuit then operates as a powerful radio transmitter when the sending key is closed, and as a sensitive heterodyne radio receiver when the sending key is open. As the tuned circuit was the same for both 80 transmission and reception, the frequency of the oscillations was substantially unchanged for sending and receiving.

85 Communication is then quickly established between two stations. Station A calls station B. Station B tunes to obtain beat note of perhaps 1000 cycles and answers call. Station A will then hear similar beat note of approximately 1000 cycles, without further tuning adjustment. The transmitting frequencies used by the two stations 90 will then differ only by the audio beat frequency necessary for heterodyne reception.

95 The operation of two or more tubes with plates and grids each in parallel will, of course, change in no way the objects and claims contained herein, which mention one, or a single tube.

100 While I have described certain forms of my invention in detail, and while I have

pointed out certain of the most obvious principles and purposes thereof, I do not intend that the language employed in the following claims shall be limited to the precise features described, but I intend that the claims shall be construed to cover all combinations which are fairly included in the language thereof, when read in view of the prior art regardless of the details and functions mentioned in the description or illustrated in the drawing.

I claim:

1. A radio signaling system, comprising a single transmitting and receiving circuit; an electron tube having a plate circuit associated with said single circuit; means operative with the plate circuit to cause said tube to oscillate strongly while transmitting; a source of potential in the plate circuit and means in said circuit for substantially reducing the potential to cause said tube to oscillate weakly while receiving.
2. A radio signaling system, comprising a single transmitting and receiving circuit; an electron tube in said circuit; means to cause said tube to oscillate strongly while transmitting; and means to cause the tube to oscillate weakly while receiving.
3. A radio signaling system, comprising a combined transmitting and receiving circuit; an electron tube having a plate circuit operatively associated with said combined circuit; a source of potential in said plate circuit; means operative in said plate circuit to control the value of said potential to cause said tube to oscillate strongly when transmitting and to oscillate weakly as a self-heterodyne detector when receiving.
4. A radio telegraph signaling system, comprising a single tuned circuit adapted both for transmitting and receiving; an electron tube having a plate circuit operatively associated with said single circuit; a source of potential in the plate circuit, and means in said circuit to control the value of the potential; and a telegraph key operative with said control means to produce strong oscillations in the tube while transmitting and weak oscillations while receiving.
5. A radio signaling system, comprising a single tuned circuit for transmitting and receiving; a single electron tube adapted to oscillate into said circuit while both transmitting and receiving; means operative with said tube to cause strong oscillations while transmitting and weak oscillations while receiving.
6. A radio signaling system, comprising a combined transmitting and receiving circuit; a tuned antenna circuit associated with said combined circuit; a single electron tube included in said combined circuit and adapted to oscillate into said antenna circuit; means to cause said tube to oscillate strongly

while transmitting and weakly while receiving.

7. A radio communicating system, comprising a single tuned circuit; an electron tube in said circuit including an associated plate circuit and means operative therewith to cause the tube to oscillate into said circuit both while transmitting and receiving; means in the plate circuit to cause said tube to oscillate strongly while transmitting and weakly while receiving; and means in the tuned circuit to maintain a substantially constant frequency both while transmitting and receiving.

In testimony whereof I affix my signature. 80
WILLIAM L. SEIBERT.
